UNITED STATES PATENT OFFICE

2,255,609

TOWEL DISPENSING CABINET

Rudolph G. Birr, Lombard, and Albert C. Grunwald, River Forest, Ill., assignors to Steiner Sales Company, Salt Lake City, Utah, a corporation of Utah

Application August 17, 1938, Serial No. 225,398

11 Claims. (Cl. 312—38)

This invention relates to improvements in dispensing cabinet constructions including a type in which when loading the cabinet with a supply of fresh toweling, it is necessary to take a terminal portion of the toweling in the hand and pass the hand and toweling upwardly through an opening in the bottom of the cabinet to a position to facilitate its connection with a soiled towel takeup roll. One object of the invention is to provide means movable to one position to provide space for facilitating introduction of the toweling toward the soiled towel roll and movable to another position to prevent introduction of the hand after the cabinet has been serviced.

This invention is also an improvement over the invention shown in Reissue Patent 17,352 in which patent means is provided for facilitating the loading operation in the manner above mentioned. In this Steiner patent part of the dispensing mechanism (a roll) is mounted on a space-making element and moves with this element toward and away from the rear wall of the outer casing. In the device of this invention no part of the dispensing mechanism is so mounted and the space-making element moves independently of any part of the dispensing mechanism.

Another object is to provide a chamber for the clean towel roll which has a single member as the sole means forming its back wall, said member being curved to conform to the curvature of the supply roll.

Features of the invention include; the scheme by which a movable element as means to facilitate or prevent introduction of the hand can be manipulated by means at the front of the cabinet for the purpose set forth; and the provision of means with which a closed door of the cabinet cooperates to positively hold a movable smoothing element in smoothing position when the door is closed.

Other features relate to the construction of the chamber for the clean towel roll by means of parts respectively carried by casing and unit; the use of a single element for the back of the clean towel chamber which functions as a space-maker, as a partition for separating clean from soiled toweling, and as a towel-smoothing means; the curving of this single element, and the relation of the rolls of the dispensing means to it and to the bottom and front wall of the cabinet to form a clean towel chamber in which there is a minimum of waste space between a full roll of clean toweling and the walls of the chamber.

Objects, features and advantages of the invention will also appear in the description of the

drawings, which illustrate a preferred embodiment of the invention and in said drawings—

Figure 1 is a vertical transverse section showing the toweling in place and the doors closed;

Figure 2 is a horizontal section on line 2—2 of Figure 1 showing among other things the partition plate and means by which it is controlled from the front of the cabinet to be forcibly held in operative position;

Figure 3 is a fragmentary plan section on line 3—3 of Figure 1; and

Figure 4 is a fragmentary vertical section illustrating how the smoother bars secure the upright plates of the inner unit.

15 In the drawings, numeral 1 generally designates the outer casing having sides 2 and 3 rounded at their tops and bottoms. The bottom of the casing 1 is indicated at 4. The numeral 5 indicates what is herein designated as a bottom door and this door is hinged as at 6 to the bottom 4 of the cabinet. This door closes about one-half of the front opening of the cabinet and forms part of the bottom and has at its upper end projections 8 which are engageable by latches generally designated 9. Numeral 10 indicates an

20 upper door or cover which forms part of the top and closes about one-half of the front opening. This top door 10 laps and covers the latching projections 8 of the lower door and the heads 25 of the latches. The lower edge 12 of the upper door and the upper edge 13 of the lower door are so formed as to define when closed a dispensing slot or opening 14 downwardly through which the toweling extends.

30 In this embodiment of the invention there is an inner unit which is detachably secured in the outer casing. The unit includes a pair of side plates (see Figures 1 and 2) respectively designated 20, 21, the vertical rear edge of each plate

35 having a flange 22 and the back having screws 23 in this instance spot welded therein, and with which openings 24 in the flanges are engaged as shown. The screws have nuts 26 to secure the flanges and therefore the plates. These

40 flanges 22 at the back are in-turned. Each plate has also at its front vertical edge a vertically extending flange 28 which is out-turned, and each side of the outer casing has an in-turned flange 29 with which the corresponding flange of the plate overlaps. The flanges 28, 29, have openings not shown, and there are screws 32 passing through the openings to secure the flanges together. There are preferably two or three screws used for each lapped pair of flanges.

45 It is noted that the plates 20, 21 are spaced

inwardly from the corresponding sides 2, 3 of the cabinet, the right plate being spaced a greater distance to provide for the reception of a time stop mechanism, not shown. On the back 35 (see Figure 1) of the outer casing near the bottom are transversely alined open top sockets 36 (only one of which is shown) made by punching the metal inwardly. These sockets may be formed in other ways. The bottom of each flange 22 of each plate fits into a corresponding socket. This prevents downward motion of the inner unit, and also prevents out-swing of the lower part of this detachable unit. These sockets also limit the unit at a position to facilitate registration of the openings 24 with screws 23, and do likewise for the openings of the front flanges 28, 29.

Another feature of the invention relates to the arrangement of two doors for the cabinet so that they cooperate to complete the formation of a discharge opening, and so that each can be swung from closed position respectively to vertical position above and below the cabinet. Another feature is that the top door forms a part of the top wall, as well as a part of the front wall of the cabinet, and that the bottom door forms a part of the bottom wall, as well as a part of the front wall of the cabinet. Thus, as both doors are opened the front-to-back dimensions of the top and bottom walls are reduced to facilitate access to the parts for servicing or repairing.

In the preferred form of the invention, the dispensing mechanism (see Figure 1) is constituted by a single unit including parts which are mounted on the two plates 20, 21 above described. This mechanism includes a pair of rollers having their axes arranged substantially in the same horizontal plane. The front roll 40 is called the measuring roll and the back roll 41 operates a soiled towel takeup roll 42 by frictional engagement with the toweling 43 thereon. Rolls 41, 40 are suitably journaled in the plates. Each roll has at one end a sprocket gear (not shown) which lies at the outer side of plate 20 or at that side nearest the side wall 2 of the cabinet. These gears are connected by a sprocket chain by which means they operate in unison so that after the toweling loop is formed and adjusted at the time of loading the cabinet, this loop is maintained by causing the same amount of soiled toweling to be taken up, as is pulled out by the user.

Associated with the measuring roll is a roll 100 known as a pinch-roll, see Figure 1. This roll is vertically movable in slots 101, of the plates 20, 21 to permit proper introduction of the towel. Upper narrower parts 102 of the slots 101 of the plates are utilized as keepers for a latch bar 103, see Figure 1, and for an arm 106 of a lock 107.

In order to prevent engagement between soiled and clean toweling as the soiled towel roll increases in diameter there is provided a guard plate 110 swingable on a pivot 111 parallel with the axes of the rolls 40, 41. This plate extends entirely across the space between the inner sides of the plates 20, 21. This guard plate is curved, and after the toweling is loaded it is swung from a rear to a forward position over the pinch roll as shown in Figure 2. Its movement toward the pinch roll is limited by a lug 113 struck inwardly from plate 21 so that the guard is slightly upwardly spaced from the toweling on the pinch roll. When in this position a concave face of the guard is opposed to the pinch and measuring rolls.

As before stated a valuable feature of this invention is the means by which space is obtained

at the back of the cabinet for facilitating introduction of the toweling, for connection with the soiled towel takeup roll, and for smoothing the toweling as it approaches the takeup roll. This means includes, see Figure 1, a plate 115 mounted to swing on a horizontal axis, provided herein by means of axially alined pivoted screws 116, one screw in each plate 20 and 21. This plate is adapted to swing forwardly to the dot-and-dash line position shown. This plate cooperates with a pair of parallel bars 118, 119, upper and lower, arranged transversely and at the back of the inner unit near the back wall of the cabinet. These bars are attached by having their ends extending through slots in the plates 20, 21. The ends as thus extended through the plates, are bent. The end of one bar is bent upwardly as at 118c and the end of the other bar is bent downwardly as at 119c (see Figures 3 and 4) to rigidly hold the parts. Bar 118 has its forward portion turned upwardly and rearwardly to form a smoothing edge 120, and bar 119 has its forward portion turned downwardly and rearwardly to form a smoothing edge 121. The upper edge of the plate 115 has a smoothing edge 123 cooperative with or lying between the edges 120, 121 for smoothing. Each of the parallel smoothing bars has two forward extensions 118a, 119a, the extension being arranged laterally near the plates 20, 21. The extensions are arranged in pairs to form guides (see Figure 2), for the soiled toweling, and to prevent over-movement of the toweling in a direction axially of the bars or axially of the rolls. The upper part of the plate is slotted as at 125 to be traversed by the guide extensions of the lower smoothing bar 119. See Figure 1.

The movable plate 115 forms the back of the chamber for the clean towel and also acts as a partition separating the clean and soiled toweling. This plate together with side plates 20, 21 and the bottom wall 4, form the clean towel supply chamber. The bottom is part of the outer casing while the sides and back are part of the removable unit. This is a feature. The unit can be removed in toto and the back 115 is removable therewith. When the plate is in its forward position a hand holding the towel can be easily passed upwardly to the roll 42. When the plate is in the full line position of Figure 1, a clean towel roll of large dimension can be placed in the chamber, see dot-and-dash line 130. The length of the radius of generation of plate 115 is about equal in length to the radius of a full roll of toweling. By using a thin plate and curving it and pivoting it and locating it as shown, an optimum of space-making and roll-receiving capacity is obtained.

In Steiner Reissue Patent 17,352 of which this invention is an improvement, there was no movable part as the sole back forming element for the clean towel chamber, nor was there a removable unit upon which any movable part was mounted to be removed therewith, nor was the chamber formed in part by the outer casing and in part by means on a removable inner unit. In the present device all of the dispensing and takeup mechanism is mounted on a unit which is stationary but which is easily removable or easily assembled, and the space-making element is arranged below both rolls and moves independently of them. Also in the present device all that is necessary is that the operator's right hand reach over the top of the rolls to meet the left hand which is pushing the towel upwardly through the space provided by the forward move-

ment of the partition and guard element 115. This element 115 also acts as a part of the soiled towel smoothing means.

In some types of cabinets the unit upon which the dispensing mechanism is mounted has been arranged pendently within the cabinet to swing outwardly on a pivot arranged at its top, and by this swinging the entire unit outwardly a space was made at the back for the upward introduction of the end of the toweling for connection with the takeup roll, but in that case the bottom of the clean towel chamber moved with the inner unit. In the present case there is a normally fixed unit upon which all of the dispensing mechanism is mounted and the chamber for the clean towel roll has a bottom formed solely by the bottom of the cabinet, and has a back and sides formed solely by parts of the unit, the back acting as a partition and being movable to permit introduction of the hand for the purpose herefore mentioned. Thus there is a back which separates soiled from clean toweling, which is movable forwardly and rearwardly and which when in position to prevent introduction of the hand is also positioned to act as a smoother for soiled wet toweling. This part is removable with the unit in this embodiment, but it may be mounted or pivoted to the bottom of the outer casing or cabinet instead of to the unit. The mounting of this plate on the unit for removal therewith is a feature as is its use as the sole back-forming element of the clean towel chamber.

When the plate 115 is in smoothing position the space previously provided for the introduction of the hand is closed so that the hand can no longer be passed upwardly. In order to move the plate to and hold it in smoothing position, as well as to move it forwardly, there are provided, see Figures 1 and 2, a pair of bars 132 one arranged at the outside of each vertical plate 20, 21 of the unit. Each bar has an in-turned end 133 loosely fitting in an arcuate slot 134 of a forwardly projecting flange 135 of the plate 115, and each bar at its forward end passes through an opening or openings 137 of vertical flanges 28 or 29 of the unit, and outer casing. In Figure 2 the left hand bar 132 passes through openings in flanges 28 and 29. The right hand bar passes through a single opening in flange 28. The rear in-turned end 133 of each bar passes through a horizontal slot 139 which is aligned with the aforesaid slots of the flanges. The forward ends 140 of these slots act as stops to limit forward motion of the plate 115. The width of the slots is less than the width of the bars 132 and the width of each bar is reduced where it passes through the slot. The placement of the clean toweling in the cabinet may act to move this swinging plate toward smoothing position. When the lower door is closed its inner surface engages the outer end of the slide bars to forcibly complete the rearward movement of the plate and to forcibly hold the plate in smoothing position.

When it is desired to service the cabinet both upper and lower doors are opened. The smoothing and partitioning plate 115 is brought to its forward position, see dotted lines, Figure 1, a fresh roll of clean toweling is held within the chamber and the end of the toweling is brought upwardly between the rolls 40 and 100, the pinch roll 100 having first been raised in its slots. The toweling is then brought downward to form a loop, thence upwardly between the space be-

tween the partition plate 115 and the back of the cabinet to the takeup roll 42. As soon as the end of the toweling has been connected with the takeup roll and a few turns made on the roll to hold it, the takeup roll 42 is then moved downwardly into the slots 44, so that the toweling engages the sanded roller 41 which is moved by means of chain 48 in unison and at the same rate of speed as the measuring roll 40. The plate 115 is now moved to the full line position of Figure 1 and the door is closed against the bars 132 whereby smoothing tension on the toweling by means of the edges 119, 120 and 123 is maintained.

15 The movable wall or plate 115 performs three functions: To separate the clean from the soiled toweling, to increase the space to facilitate introduction of the toweling for connection with the soiled towel takeup roll, and to cooperate with other means in the cabinet for smoothing the wet toweling on its way to the takeup roll.

20 The movable partition may slide, or it may swing as it is herein shown, to provide the space for the hand introduction of the towel upwardly. It will be understood that the smoothing function may be dispensed with and other smoothing means provided in the cabinet. It is enough to mount the partition in any suitable way. A feature is to mount the partition so as to be removed with the unit.

25 The latches hold the bottom door closed to in turn secure the bars 132 against outward movement. The plate 115 is thus positively held in a position to prevent tampering.

30 The relations of the smoothing edges may be varied from that shown and there is no intention to be limited to the exact spacial relations shown.

35 We claim as our invention:

1. A towel dispensing apparatus including a cabinet having side walls and having therein between said side walls a soiled towel takeup roll, said cabinet having an opening upwardly through which the toweling can be introduced to be connected to the take-up roll, an element within the cabinet and between said side walls movable forwardly and rearwardly in relation to the back wall of said cabinet to provide sufficient space to allow hand introduction of the toweling for connection with the takeup roll, a door on the cabinet, and means passing through said side walls and connecting with said element for moving the same respectively to prevent or permit introduction of the hand, said means including parts which are translatable to be engaged by the closed door to hold the element in position to prevent introduction of the hand.

2. A towel dispensing apparatus including a cabinet having therein side walls and having between said side walls a soiled towel takeup roll, said cabinet having an opening upwardly through which the toweling can be introduced to be connected to said take-up roll, an element within the cabinet and between said side walls which is movable forwardly and rearwardly in relation to the back wall of said cabinet to provide sufficient space to allow hand introduction of the toweling for connection with the takeup roll, said element having towel smoothing means, a door on the cabinet, and means for moving said element respectively to prevent or permit introduction of the hand, said means including bars, each translatable and each having means passing through a slot in a corresponding side wall and connected to said element, said bars being en-

gagable by the closed door to hold the element in position to prevent introduction of the hand, and smoothing means on the cabinet engaged by the soiled toweling and against which the smoothing means of said element holds the soiled toweling when said element is in position to prevent introduction of the hand.

3. A towel dispensing apparatus including a cabinet having therein a soiled towel takeup roll, said cabinet having an opening upwardly through which the toweling can be introduced to be connected to said take-up roll, a partitioning element which is movable toward and away from a wall of the cabinet to provide sufficient space to allow hand introduction of the toweling for connection with the takeup roll, a door on the cabinet, and means for moving said partitioning element toward and away from the cabinet wall respectively to prevent and permit introduction of the hand, said means including two translatable bars and means connecting each bar to said element, said bars being engageable to be moved by said door when closing, to move said partitioning element to a position to prevent introduction of the hand, the closed door thereafter acting to hold the bars to secure the element in that position.

4. A towel dispensing apparatus including a cabinet having a chamber for a clean towel supply roll, said chamber having side walls which are detachably fastened to a stationary rear wall, the bottom wall of which cabinet forms the sole support for the roll, a soiled towel takeup roll above the chamber, said cabinet having an opening upwardly through which the toweling can be introduced to be connected to said take-up roll, the rear wall of said chamber being entirely formed by a partitioning element which separates the clean from the soiled toweling as the latter moves upwardly to the soiled towel takeup roll, said partition element being pivoted by its bottom to said side walls immediately adjacent said bottom wall and being movable toward and away from the rear wall of the cabinet to provide sufficient space to allow hand introduction of the toweling upwardly for connection with the take-up roll.

5. A towel dispensing apparatus including a cabinet having a door and having therein, a soiled towel takeup roll, said cabinet having an opening upwardly through which the toweling can be introduced to be connected to said take-up roll, an upright pivoted plate within the cabinet which is movable independently of side walls of the cabinet toward and away from the rear wall of the cabinet to provide sufficient space to allow hand introduction of the toweling for connection with the takeup roll, a pair of bars one attached to each opposite side of said movable plate, means mounting said bars for translation on the side walls to move the plate toward and away from a rear cabinet wall respectively to prevent and permit introduction of the hand, said bars having portions disposed for engagement by said door to move the bars to move the plate to a position to prevent introduction of the hand, the closed door thereafter acting to hold the bars in said position, said bars when in holding position projecting sufficiently at the front of the cabinet to be engaged by the fingers and pulled outwardly.

6. A towel dispensing apparatus including an outer casing having a door and having detachably secured therein a stationary unit upon which a dispensing mechanism is mounted, a soiled

towel takeup roll operated by said mechanism, the bottom wall of the outer casing forming the sole support for a roll of clean toweling, the bottom wall of said outer casing having an opening sufficiently large to allow the hand to be passed upwardly behind a roll of clean toweling which rests on the bottom wall of the outer casing, a forwardly, convexly, curved partition element arranged rearwardly of the clean towel roll, and means pivoting the partition by its lower side to the stationary unit immediately adjacent the bottom wall of the casing, said partition being movable independently of said stationary unit forwardly to provide sufficient space to permit hand introduction of the toweling upwardly through said opening, said pivoted partition having a rearwardly turned upper edge which acts to smooth the toweling on its way to the take-up roll.

7. A towel dispensing cabinet comprising, an outer casing, said casing having a towel dispensing mechanism therein, including side plates secured in the cabinet each having a front flange, said dispensing mechanism having a soiled towel takeup roll and said casing having in its bottom an opening to allow passage of the hand upwardly for connection of the toweling with the take-up roll, a pivoted partition element between the side plates adapted to swing to a position to prevent passage of the hand to connect the toweling with the roll, means with which means on said partition when in said position cooperates to smooth the toweling before it reaches the take-up roll, said partition acting as the back wall of a clean towel supply chamber, a door closing the supply chamber and means connected to said partition element slidable on said plates and slidable in said flanges and accessible at the front of the cabinet and operable by hand for moving said partition element to prevent or permit passage of the hand through the opening, said means projecting at the front of the cabinet and being engageable by the door to be held against outward movement when the door is closed, whereby to hold the partition in towel smoothing position and prevent introduction of the hand.

8. A towel dispensing cabinet comprising, an outer casing, said casing having a towel dispensing mechanism therein, including side plates secured in the cabinet each having a front flange, said dispensing mechanism having a soiled towel takeup roll and said casing having in its bottom an opening to allow passage of the hand upwardly for connection of the toweling with the take-up roll, a pivoted partition element between the plates adapted to swing to a position to prevent passage of the hand to connect the toweling with the roll, means with which means on said partition when in said position cooperates to smooth the toweling before it reaches the take-up roll, said partition acting as the back wall of a clean towel supply chamber, a door closing the supply chamber and bars connected to said partition element slidable on said plates and slidable in said flanges and accessible at the front of the cabinet and operable by hand for moving said partition element to prevent or permit passage of the hand into smoothing and non-smoothing relation with said smoothing means, said bars projecting at the front of the cabinet and being engageable by the door to be held against outward movement when the door is closed, whereby to hold the partition in towel smoothing position and prevent introduction of the hand.

9. A towel dispensing cabinet comprising, an outer casing having a bottom, said casing having a unit towel dispensing mechanism therein, including sides, said dispensing mechanism having a soiled towel take-up roll and said casing having in its bottom an opening to allow passage of the hand upwardly for connection of the toweling with the take-up roll, a partition element within the cabinet pivoted on and between said sides to swing to a position to prevent passage of the hand to connect the toweling with the roll, means with which means on said partition when in said position cooperates to smooth the toweling before it reaches the take-up roll, said partition acting as the back wall of a clean towel supply chamber, said sides being detachably connected to the casing, whereby the entire unit, including the smoothing means, can be removed.

10. A towel dispensing cabinet comprising, an outer casing having a bottom, said casing having therein a unit towel dispensing mechanism therein, including sides, said dispensing mechanism having a soiled towel take-up roll and said casing having in its bottom an opening to allow passage of the hand upwardly for connection of the toweling with the take-up roll, smoothing means cross-connecting and securing said sides together, a partition element within the casing pivoted on

and between said sides to swing to a position to prevent passage of the hand to connect the toweling with the roll, and having smoothing means cooperable with the aforementioned smoother means to smooth used toweling, said partition acting as the back wall of a clean towel supply chamber, said sides being detachably connected to the casing, whereby the entire unit, including the partitioning element, and smoothing means can be removed.

11. A towel dispensing apparatus including a cabinet comprising an outer casing and an inner unit, and means detachably securing the said unit to the outer casing, said inner unit comprising a pair of spaced upright plates, a pair of smoother bars cross-connecting the plates, and means by which said bars act to secure said plates in unit-forming relation, a soiled towel takeup roll journaled on said plates, said bars acting to smooth the soiled toweling on its way to said takeup roll, and a movable element having smoothing means adapted to cooperate with said bars and toweling to hold the towel in smoothing relation with said bars, said movable element being pivoted to and extending between said plates.
